UNITED STATES PATENT OFFICE

MORRIS KANOFSKY, OF CHICAGO, ILLINOIS, ASSIGNOR TO JACK STEIN, OF CHICAGO, ILLINOIS

DESIGN FOR A FLORAL BASKET

Application filed July 10, 1931. Serial No. 40,484. Term of patent 14 years.

To all whom it may concern:

Be it known that I, MORRIS KANOFSKY, formerly a subject of Russia, having received my first naturalization papers in the United States, and now residing at Chicago, in the county of Cook and State of Illinois, have invented a new, original, and ornamental Design for a Floral Basket, of which the following is a specification, reference being had to the accompanying drawings, forming a part thereof.

The body of the basket is formed from a single rectangular piece of thin gage sheet metal which is bent to form a bottom and sides as shown in the drawings.

I claim:

The ornamental design for a floral basket, as shown and described.

In witness whereof, I hereunto subscribe my name this 8th day of July, 1931.

MORRIS KANOFSKY.
